UNITED STATES PATENT OFFICE

2,300,665

REFRIGERATOR CAR CONSTRUCTION

Garth G. Gilpin, Riverside, Ill., assignor to Standard Railway Equipment Manufacturing Company, Chicago, Ill., a corporation of Delaware

Application February 17, 1940, Serial No. 319,404

8 Claims. (Cl. 105—404)

The invention relates to railway rolling stock and more particularly to so-called "refrigerator cars" which are used to transport perishable commodities, such as vegetables, fruits, berries, frozen foods and fish. Such commodities must be maintained at a substantially even temperature to avoid decay. Heat or refrigeration is applied to the commodity while in transit depending upon the weather. Certain commodities (such as potatoes and oranges) generate heat and gases which must be removed by ventilation. A railway car, therefore, to haul perishable commodities must be arranged to cool, heat or ventilate the commodity while in the car. This applies, of course, if the car is running or standing still.

Various fruits, such as oranges, lemons and grapefruit from California and Florida, apples from Washington and Oregon, and various vegetables from such States as California, Colorado, Illinois and Georgia are loaded into the refrigerator cars and shipped; i. e., the cars actually start moving with destination unknown and without any consignee. To facilitate selling the commodity while enroute, grades for quality have been established. "Units" for volume have also been established by adoption of a standard size box for each fruit and the size of the fruit is designated by the number of that fruit in the box (which is stencilled on each box); the number of such boxes which can be loaded in a standard size refrigerator car is a "unit." To be more specific, the inside dimensions of a conventional end bunker refrigerator car are approximately 40 feet long, 8' 3" wide and 7 feet high, and an ice bunker is positioned at each end of the car so that the loading space between the bunkers is about 33 feet. Such a car will hold and refrigerate 462 boxes of oranges or 420 boxes of lemons from California and such number of boxes constitutes a unit of the specific fruit of a known grade and size.

When the owner (usually through a cooperative association) sells his fruit, the shipment is diverted while enroute to the purchaser. It requires approximately seven days to transport fruit from California to Chicago; ten days to New York and twelve days to Boston; this system allows the owner to take advantage of changing market conditions. If the commodity is not sold enroute it is consigned to one of the several perishable commodity auction markets in the larger cities where it is sold before it becomes unusable.

A new type of refrigerator car has been de-

veloped by my assignee which is described and claimed in Bonsall Patent No. 2,136,999 of November 15, 1938, wherein the refrigerant containers are positioned adjacent the ceiling of the car with drip pans spaced therebelow. Air in the space below the refrigerant containers, being cooled by the refrigerant in the containers (preferably ice or ice and salt), flows through vertical flues into a space below a foraminous secondary flooring below the lading and coming into contact with the lading, is warmed thereby and rises to the space below the refrigerant container, where it is cooled by contact with the refrigerant and repeats the cycle. This is called lateral or crosswise air circulation.

The Bonsall improved refrigerator car eliminates the necessity of the end ice bunkers, thus increasing the available lading space from 33 to 40 feet without increasing the train length or overall length of the car. Furthermore, in the conventional end bunker car, hereinbefore described, it is usually necessary to leave at least two feet between the top of the lading and the ceiling of the car for the warmed air to return to the end bunkers, whereas in Bonsall's top bunker car the lading can be loaded up to the ceiling, thus materially increasing the volume and weight of the lading without decreasing the efficiency of the refrigeration of the lading (in fact, tests show better refrigeration). Again to be specific: The conventional forty foot end bunker car holds 462 boxes of oranges (which is a unit¹ for that particular fruit), whereas a Bonsall top bunker car was actually loaded and shipped with 840 boxes of oranges, or one and eight-tenths units. The sizes and weights of the boxes are commercially recognized standards.

One of the objects of the invention is to provide a refrigerator car that will hold and refrigerate 40 more than an established unit of lading and which shall include means to segregate one unit from the remainder of the load so that said unit may be loaded and unloaded without disturbing the remainder of the load. The said remainder 45 may be another unit.

Another object is to provide a partition between the unit and the remainder which may be removed when not wanted; for instance, when more than a unit load is consigned to an auction market.

Another object is to provide an insulated partition so that the commodities on opposite sides of the partition may be maintained at different temperatures.

Another object is to provide a wall or parti-

tion which is movable longitudinally of the car to divide the lading space of the car into equal or unequal sizes, as conditions may require, and to provide means to fasten said wall or partition in any of such positions.

Another object is to provide a refrigerator car with a partition so as to divide the car into a pair of compartments and to provide access to each compartment through doorways positioned at the corners of the car or somewhat distant from the corners but relatively remote from the center of the car. The advantages of such an arrangement are that the compartments can be loaded simultaneously from either the same side of the car or from opposite sides; in either case, the men loading one compartment may work free from interference from the men loading the opposite compartment.

The modern steel sheathed refrigerator car has substantially superseded the wood sheathed car wherein the framework of the car, either wood or steel, was comprised of trusses embedded within the walls. In the steel sheathed car, the walls function somewhat as girders and the thrusts upon the end walls are transferred to the side walls, not only to the side plate and side sill, but also distributed over the sheathing between the plate and sill. A doorway in a side wall near a corner of the car inherently prevents transfer of end wall thrusts to the side sheathing. It is an object of my invention to overcome this deficiency by providing means by which the door or doors transmit end wall thrusts to the side sheathing.

Commodities hauled in refrigerator cars usually must be carefully handled. Fruits, for example, bruise easily and must be securely braced when loaded to prevent the service movements of the car causing the lading to shift. A conventional end bunker refrigerator car has doorways at the center of the side walls. A common method of loading fruit in such a car is to place the crates in the car, working from the ends of the car toward the center. When the car is thus filled except for a relatively small space at the doorways, a "squeezer" is inserted in this space and the crates are pushed toward the end walls of the car. In other words, the crates in each end of the car serve as a backing for the "squeezer" to compress the crates in the opposite end. Finally, either temporary bulkheads are installed to retain the crates in this position or the enlarged space thus created is filled with additional crates of fruit. It is another object of my invention to position each doorway with one edge thereof substantially flush with the end wall lining, the car being provided with a partition as hereinabove described. The advantages of such an arrangement are two-fold; first, the "squeezer" may be inserted between the crates and the end wall of the car, thereby providing a more secure backing and second, fewer temporary bulkheads are required to brace the lading.

The objects and advantages hereinabove pointed out of a refrigerator car having doors in the side walls adjacent the corners of the car apply either to the conventional end bunker car or to the hereinabove described overhead bunker car. It is pointed out, however, that in the end bunker car, the refrigerating medium is at the ends of the car and that the regions of the car remote from said medium are often relatively warm because the refrigerated air does not flow the required distance. When the partition is positioned nearer one end than the other, certain parts of the larger compartment are more remote from

the refrigerating source than usual and the temperature is therefore less uniform. In the case of the top bunker car, however, the partition may be placed in any position along the length of the car and the refrigeration efficiency remains unimpaired because the refrigerated air is supplied from the sides. The length of a compartment, therefore, has no effect whatsoever upon the temperatures within the compartment.

Another object of my invention deals with the provision of a partition in a refrigerator car having a refrigerant bunker near each end wall. By disposing the partition above the floor racks and providing a foraminous upper portion, I provide means by which one of the compartments, if larger than the other compartment, may be refrigerated by cold air from the bunker adjacent the smaller compartment.

Another object of my invention is to position the doorways adjacent the refrigerant bunkers so that the cold air flowing from the bunkers compensates for the infiltration of warm air through the door seals. The air within the car has its lowest temperature immediately after leaving the bunkers and is therefore well adapted to prevent the undesirable conditions which result from heat leakage at the doorways.

Other objects and advantages of my invention will be apparent from the following detailed description by referring to the accompanying drawings.

In the drawings:

Fig. 1 is a longitudinal elevational section through a refrigerator car embodying my invention.

Fig. 2 is a plan section of the car taken on line 2—2 of Fig. 1.

Fig. 3 is a view analogous to a part of Fig. 2 showing a modified form of corner construction.

Fig. 4 is a transverse section taken on lines 4—4 of Fig. 1.

Fig. 5 is a partial plan section showing a modified construction.

Fig. 6 is a view similar to Fig. 3 showing another modified construction. The section is on line 6—6 of Fig. 7.

Fig. 7 is an elevational view of the structure shown in Fig. 6.

Fig. 8 is an enlarged section on line 8—8 of Fig. 7.

Fig. 9 is a longitudinal elevational section of a conventional end bunker car embodying my invention.

Fig. 10 is a plan section on line 10—10 of Fig. 9.

Fig. 11 shows a modified form of partition.

Fig. 12 is a plan section of another modified construction.

Figs. 1 to 5 inclusive show my invention particularly adapted to an overhead bunker refrigerator car. The general parts of the refrigerator car shown in such figures are insulated roof 1; end walls 2; side walls 3; floor 4; hatches 5; refrigerant containers 6; side wall flues 7; foraminous floor rack 8 and space 9 between rack 8 and floor 4. A refrigerant container 6 is positioned directly below the roof 2 and adjacent a side wall 3. A drip pan 12 is provided below the container 6 and a partition 14 is disposed in an upstanding position at the edge of the drip pan 12. The drip pan 12 and partition 14 cooperate with the roof 2 and side wall 3 to form an enclosing structure 11 around the container 6, an air inlet opening 15 being provided by spacing the partition 14 from the roof 2. An air discharge opening 17 which leads to a flue 7 is formed by spacing the

drip pan 12 from the wall 3. Cars of this type commonly have a row of refrigerant containers 6 near each side wall 3 and spaced apart at the center of the car. The partitions 14 are also spaced apart to form a duct 16 which communicates between the lading chamber 18 and openings 15.

Air circulation is as follows: Air in the lading chamber 18 is warmed by contact with the lading and rises to enter the enclosing structures 11 through the duct 16 and air inlet openings 15. The air is cooled by contact with the refrigerant containers 6 and falls by reason of its greater density through the discharge openings 17 and flues 7 to the space 9 whence it rises through the rack 8 to the lading chamber 18.

The end walls 2 and corner posts of the structures shown herein may be formed with corrugations as disclosed in Patent No. 2,185,168 issued to Jumper et al. on December 26, 1939. The refrigerant containers 6 may be supported as shown in Figs. 10 and 11 of co-pending application by C. D. Bonsall, Serial No. 286,138 filed July 24, 1939.

The refrigerator car is provided with a partition 25 which extends substantially between the side walls and substantially between the upper and lower boundaries of the lading chamber 18 so as to divide said chamber into a pair of compartments 26. The partition 25 may be fixed in the desired position within the car as shown in Fig. 5 or may be removable or movable to any one of a plurality of positions within the car as shown in Figs. 1, 2 and 4. The partition may be an uninsulated partition 28, as shown in Fig. 5, or an insulated partition 29, as shown in Figs. 1, 2 and 4, where it is desired to maintain a temperature gradient between the compartments 26.

Doorways are preferably provided for access to either of the compartments 26 from either side of the car. In Fig. 1 the doorways 31 are provided near the end walls 2. Each end wall 2 preferably comprises an outer sheathing 35, a lining 36 and insulation 38 disposed therebetween. Each corner post 37 preferably comprises angularly disposed arms 39, 41, the arm 39 preferably being secured to the sheathing 35 and the arm 41 to the flange 42 of the sheathing 35. The sheathing 35 may have corrugations as hereinabove pointed out. A doorpost 44, preferably wood, is rigidly secured to the corner post 37. Another doorpost 46, disposed in spaced relation to the doorpost 44, is secured to and forms a part of the side wall 3 in the conventional manner. The closure for the doorway 31 may be a single door 47 hinged (49) to the corner post 37 or doorpost 44, a single door hinged to the opposite doorpost 46 or double doors hinged to both doorposts as hereinafter pointed out.

In the modification shown in Fig. 3, the corner post 54 comprises the usual angularly disposed arms 56, 57 and, in addition, the inwardly directed flange 59 substantially parallel with and in spaced relation to the arm 57. The flange 59 may be connected to the arm 57 by suitable ties or braces. A wood door-post 61 is secured to the corner post 54, preferably to the flange 59; the other doorpost 62 is secured to and forms a part of the side wall 3 of the car and is disposed in spaced relation to the doorpost 61. The door 64 may be hinged (65) to the doorpost 62 so as to swing to a flatwise relation with the side wall 3 instead of protruding beyond the end of the car.

As shown in Figs. 2 and 3, flues 7 are associated with the side walls 3 of the car to con-

duct cold air from the refrigerant enclosures to the space 9 under the floor rack. In order to supply a uniform amount of cold air to the interior of the car and to compensate for heat leakage through the door seals, flues 67 are commonly, but not always, provided in the doors 47, 64 for flow of cold air. To provide additional compensation for leakage through the door seals, flues 68 may also be provided in the end walls 2, which flues function in a manner similar to the side wall flues 7 and door flues 67. (See Fig. 3.)

The partition 25 may be of any construction adapted to retain the lading during service movements of the car. In Figs. 1, 2 and 4, the partition 29 comprises a pair of spaced apart metallic plates 70 secured in spaced apart relation by the upper and lower frame members 72, 73. The plates 70 are preferably formed with vertically extending corrugations 75 and insulation 76 is provided between the plates 70. Sheathing 78, preferably wood, is secured to the outer sides of the plates 70 to form a smooth surface. Suitable means are provided by which the partition 29 may be moved lengthwise of the car and also for securing the partition in one of a plurality of positions. In the drawings, the means shown comprises rollers 79, 80 mounted upon the partition 29 at the upper and lower corners thereof. The upper rollers 79 engage tracks 82 mounted upon the upper parts of the side walls 3 and the lower rollers 80 engage the tracks 83 mounted in the lower part of the car. The partition may be secured in the desired position by any suitable means, such as the clips 85 and bolts 86 adapted to engage the upper tracks 82.

In the modification shown in Fig. 5, the lading chamber 18 is divided into compartments 26 by the partition 28. The partition 28 is comprised of a plurality of spaced apart columns 90 having facing 91 secured thereto, preferably on both sides thereof. The partition 28 is shown secured to the side posts 93 by the bolts 94 although it is apparent that the partition could be movable as shown in Fig. 1 and equally apparent that the insulated partition 29 shown in Fig. 1 could be mounted in a fixed position as shown in Fig. 5. Access to each compartment 26 is provided by the doorways 96 positioned a substantial distance (97) from the end walls 2 so that deflections of the end wall 2 and corner posts 37 do not affect the fitting of the doors 99 in the doorways 96. It is intended that, although the distance 97 is substantial, the doorways 96 in the same side of the car are spaced apart a sufficient distance to provide a large range of sizes of compartments 26.

In the conventional type of refrigerator car having the doorways at the center of the car, a part of the thrust upon the end walls is transmitted to the side sheathing of the car. For reasons hereinabove pointed out, I found it desirable to position doorways in the side walls near the corners of the car. Such an arrangement destroys, to a certain extent, the connection between the side wall and end wall; the construction shown in Figs. 6 to 8 overcomes this difficulty.

In Figs. 6 to 8, the doorpost 44 is secured to the corner post 37 and the doorpost 46 is disposed in spaced relation to the doorpost 44, as described in reference to Fig. 2. A pair of doors 104, 105 are hinged to the doorposts 44, 46 respectively. On the face of each door 104, 105 is secured a rod 107 which, in the form shown, are inwardly facing channel members secured to the doors by lateral flanges 108. The rods 107 are mounted

upon the doors 104, 105 remote from the hinges 110 and have their upper (111) and lower (113) parts projecting above and below the door respectively. Spaced apart brackets 114 are secured to the side wall 3 above and below the doorway, parts of the brackets 114 preferably being secured to the side plate 116 and side sill 117. The brackets 114 are arranged to form pockets 119 in which the upper and lower parts 111, 113 of the rods 107 fit when the doors 104, 105 are closed. When the end wall 2 receives a thrust, the thrust is carried through the hinges 121 to the door 104 and by the door 104 to the rod 107 associated therewith. The relatively small part of side wall 3 (or side plate 116 or side sill 117) between the pockets 119 transmits the thrust to the rod 107a associated with the door 105. The door 105 and hinges 122 transfer the thrust to the side wall 3 where it is distributed in the conventional manner.

It is to be understood that the interlocking means shown in Figs. 6-8 is not limited to an arrangement wherein two doors are used to close the door opening. The arrangement may be equally well adapted to a single door, such as is shown in Fig. 2.

Figs. 9 and 10 show my invention adapted to a refrigerator car having a refrigerant bunker 130 adjacent each end wall 131. The bunker 130 extends substantially between the roof 133 and floor 134 of the car. A bulkhead 136 forms one wall of the bunker 130 and separates the bunker 130 from the lading chamber 137. The bunker 130 usually comprises grates 139 for supporting the refrigerant and the walls 140, often foraminous, which form the passages 142 for air flow. Air within the bunker 130, being cooled by contact with the refrigerant, descends by reason of its greater density to flow through the opening 143 below the bulkhead 136 and into the space 145 below the floor rack 146. The cold air then permeates upwardly through the lading chamber 137, thereby refrigerating the lading, and finally returns through the opening 148 above the bulkhead 136 to the bunker 130, from where the cycle is repeated.

The lading chamber 137 is divided into a pair of compartments 149 by a partition 151 which may be insulated or uninsulated, fixed or movable as hereinabove described. In Figs. 10 and 11, the partition 151 is shown movable by the means shown in Figs. 1, 2 and 4 although any other suitable means may be used.

Access to each compartment 149 is provided by a doorway 155 in each side wall 156. The doorways 155 may be positioned in any convenient location, but it is pointed out that they should be spaced apart a sufficient distance to provide a reasonable variation in the relative sizes of the compartments 149. In the drawings, the doorways 149 are shown with one edge 158 thereof substantially flush with the bulkhead 136. Advantages of this arrangement are two-fold: (1) Maximum range is provided for movement of the partition 151; and (2) the heat leakage through the door seals is compensated for to a certain extent by the cold air flowing from the bunker 130. In the conventional car having the doorways at the center and the refrigerant bunkers at the ends of the car, the interior of the car is warmest at the center, due partly to the great distance from the source of refrigerant and partly to the heat leakage through the door seals. The air flowing from the bunker has the lowest temperature of any air in the car and by

positioning the doorways 155 adjacent the bunkers 130, I take advantage of this low temperature to compensate for the infiltration of warm air at the doorway.

Fig. 11 shows a partition 165 which may be used in place of the partition 151 in Figs. 9 and 10. It is pointed out that in Figs. 9 and 10, each compartment 149 is refrigerated solely by the bunker 130 adjacent thereto because the substantially imperforate partition 151 prevents the air returning from either compartment 149 to the bunker 130 at the opposite end of the car. Consequently, when the compartments 149 are of unequal size, the larger compartment is likely to be deficient in refrigeration because of the remoteness of certain parts thereof from the refrigerant source. The use of the partition 165 permits the compartments 149 to be refrigerated substantially free of interference by a partition. It is pointed out that the partition 165 is positioned entirely above the floor rack 146, thereby permitting flow of air under the rack from either bunker 130 into the compartment 149 at the opposite end of the car. The upper part 166 of the partition is foraminous to provide for flow of warm air from one compartment through the other compartment to the bunker adjacent the second mentioned compartment. Therefore, either compartment 149 is likely to be partly refrigerated by the bunker 130 at the opposite end of the car.

Fig. 12 shows a modification in which a refrigerant bunker 170 is positioned intermediate the end walls 171, preferably near the center of the car. Two lading compartments 173 are provided, one on each side of the bunker 170. The bunker 170 is substantially similar to the bunker 130 of Fig. 10, a bulkhead 174 being provided on each side thereof. Access to the compartments 173 is provided either by doorways 176 positioned adjacent the end walls 171, with the advantages hereinabove pointed out, or by doorways 178 positioned adjacent the bulkheads 174. Doorways 178 positioned in the latter position are advantageous in the respect pointed out in reference to Figs. 9 and 10.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

I claim:

1. In a refrigerator car having a side wall and an end wall, said side wall having spaced apart door posts having a doorway therebetween, said end wall being secured to one of said door posts to form a corner post of the car, a door attached to said last mentioned post and adapted to form a closure for said doorway, and means to transmit longitudinally outward end wall thrust to the portion of the side wall adjacent said doorway comprising operatively engaged members carried by said door and side wall respectively.
2. In a refrigerator car having a side wall and an end wall, said side wall having spaced apart door posts having a doorway therebetween, a corner post having said end wall secured thereto, one of said door posts being rigidly secured to said corner post, a door attached to said last mentioned door post and adapted to form a closure for said doorway, and means to transmit longitudinally outward end wall thrust to the portion of the side wall adjacent said doorway

comprising operatively engaged members carried by said door and side wall respectively.

3. In a refrigerator car having a side wall and an end wall, said side wall having spaced apart door posts having a doorway therebetween, said end wall being secured to one of said door posts to form a corner post of the car, a door adapted to form a closure for said doorway, and means to transmit longitudinally outward end wall thrust to the portion of the side wall adjacent said doorway comprising hinge means mounting said door upon said corner post and members carried by said door and said side wall respectively which engage when the door is closed to prevent relative movement between said door and said side wall in the plane of the side wall.

4. In a refrigerator car having a side wall and an end wall, said side wall having spaced apart door posts having a doorway therebetween, said end wall being secured to one of said door posts to form a corner post of the car, a door adapted to form a closure for said doorway, and means to transmit end wall thrust to the portion of the side wall adjacent said doorway comprising hinge means mounting said door upon said corner post, and interlocking means to prevent coplanar relative movement between said door and said side wall, said interlocking means comprising vertical rods mounted upon and extending beyond said doors and adapted to seat in outwardly opening pockets on the side wall.

5. In a refrigerator car having spaced apart side walls and spaced apart end walls which enclose a lading chamber, a bulkhead in spaced relation to each of said end walls to provide refrigerant chambers therebetween, refrigerating means in said refrigerant chambers, a partition intermediate said bulkheads which divides said lading chamber into a pair of lading compartments, and a doorway leading to each of said compartments, an edge of each of said doors being substantially flush with one of said bulkheads.

6. In a refrigerator car having spaced apart side walls and spaced apart end walls, a refrigerant bunker extending substantially between said side walls intermediate said end walls to provide a lading compartment on each side thereof, bulkheads disposed between said bunker and said lading compartment, and a doorway leading to each of said compartments having an edge thereof substantially flush with one of said bulkheads.

7. In a railway car having spaced apart corner posts, an end wall extending between and secured to said corner posts, a doorway in a side wall adjacent said end wall, a door for closing said doorway hingedly mounted upon one of said posts, and means to transmit longitudinally outward end wall thrust to the portion of the side wall adjacent said doorway comprising operatively engageable members carried by the door and side wall respectively.

8. In a refrigerator car having a side wall and an end wall, said side wall having spaced apart door posts having a doorway therebetween, said end wall being secured to one of said door posts to form a corner post of the car, a pair of doors adapted to form a closure for said doorway, and means to transmit longitudinally outward end wall thrust to the portion of the side wall adjacent said doorway comprising hinge means mounting said doors upon said corner post and the opposite door post, respectively, and members carried by said doors respectively, which engage to prevent coplanar relative movement between said doors.

GARTH G. GILPIN.
